ATTORNEY

UNITED STATES PATENT OFFICE.

HERBERT ABRAHAM, OF NEW YORK, N. Y., ASSIGNOR TO THE RUBEROID CO., A CORPORATION OF NEW JERSEY.

ROOF.

Application filed June 16, 1924. Serial No. 720,390.

To all whom it may concern:

Be it known that I, HERBERT ABRAHAM, a citizen of the United States, residing at the city, county, and State of New York, have 5 invented a certain new and useful Improvement in Roofs, of which the following is a specification.

This invention relates to roofs composed of flexible shingles laid upon a sheathing in 10 overlapping courses.

In such roofs it is necessary to hold down the lower ends of the shingles so as to prevent them from curling or bending.

Due to changes in climatic conditions and 15 variations of temperature, the sheathing of the roof, and to a lesser degree the shingles themselves, will expand and contract. Where the lower ends of the shingles are 20 rigidly held or locked in place, such expansion and contraction will cause the shingles to buckle or become distorted, thus giving the roof an unsightly appearance.

The principal object of this invention is to provide a roof construction wherein the 25 lower ends of the shingles of each course are held down flatly in such manner as to permit of expansion or contraction of the sheathing or shingles without distorting the shingles.

30 I attain this, as well as other objects, by means of the construction hereinafter described, and pointed out in the claims.

In the accompanying drawings, illustrating one embodiment of the invention;

35 Figure 1, is a plan view of a portion of a roof covering embodying the invention;

Fig. 2, is a detail plan view on a larger scale;

40 Fig. 3, is a section on the line 3—3 of Fig. 2;

Fig. 4, is a front end view of one of the flexible shingles;

Fig. 5, is a top plan view of the fastening member; and

45 Fig. 6, is a front elevation thereof.

Referring to the drawings, 1 indicates the flexible shingle made of felt or fibrous material saturated and coated with bituminous compositions, and preferably faced with 50 crushed slate or other facing material. Each shingle has a narrow opening 2 near its lower end, which opening extends through the shingle and forms an eye for receiving the tongue 6 of the fastener 5. A metallic 55 strip or edging 3 extends across, and is se-

cured to, the lower end of the shingle adjacent to the opening 2. This edging serves to reenforce the end so as to prevent the shingle from tearing when it is hooked down. While I prefer to form the hole 2 just above 60 the edging 3, it is obvious that if desired the opening may be formed through the edging. The lower end of the shingle may be underfolded as seen in Fig. 3. In that case the edging is preferably wrapped in 65 and around the fold so as to protect the bend and to provide a butt of increased thickness. The edging preferably has a depression 4, in line with the opening 2, to facilitate hooking the shingle upon the tongue 70 and to accommodate the projecting end of the tongue.

The fastener 5 is preferably made of any suitable form of metal, and comprises a body portion having a tongue-like projection 6 at 75 substantially its middle, which tongue preferably, though not necessarily, extends in the plane of the body portion. The body portion is provided with nail receiving holes or eyes 7—7, and it may be formed with 80 spaced downwardly extending lugs 8—8. These lugs are adapted to abut against the side edges of the pair of shingles on which the fastener is secured and form a guide for properly positioning the fastener. 85

In covering a roof, the shingles are laid upon the sheathing in the manner illustrated in Figures 1 and 2. A fastener 5 is positioned on each pair of adjacent shingles of a course with the body of the fastener 90 spanning the space between the shingles and with the tongue 6 directed toward the eaves. The fastener is now secured to the shingles by nails 9 driven through the nail holes 7, which nails also serve to fasten the shingles to the roof sheathing. The shingles of the next upper course are then located by passing the opening or eye 2 of each shingle over the tongue 6 of a fastener 5 of the first mentioned course. The shingles 95 of said upper course are in turn provided with fasteners 5 and nailed as above described, and these operations are repeated in laying the succeeding courses.

It will be seen that the lower end of each 105 shingle is firmly held down by projecting end of a tongue 6 but in such manner that it may slide lengthwise of the tongue to permit of expansion and contraction. As the opening in each shingle is closed by the 110

2

tongue, and as it is disposed over an imperforate body portion of a shingle of the second lower course, no leakage can occur. Furthermore, with fasteners of the preferred construction described no guide lines are required in laying the shingles because the position of the fasteners on each course will definitely and properly locate the shingles of the succeeding course with the desired amount of overlap.

Various modifications in the details described may be made without departing from the spirit or scope of this invention. Also, the construction may be used on a siding as well as on a roof.

What I claim is:

1. In a roof composed of overlapping flexible shingles each having a preformed opening through its lower end portion, a metallic fastener secured to two adjacent shingles of a course and having a tongue-like member that passes horizontally through the opening in an overlapping shingle of the next upper course and lies upon the lower end of said shingle, whereby to hold down the end but to permit of a sliding motion of the shingle on the tongue-like member.

2. The combination of a shingle having a preformed opening through its lower end

portion, and a fastener having a projecting portion that passes horizontally through the opening with its end lying over the upper surface of the lower end of the shingle, whereby to hold down the shingle end in a manner to permit of sliding movement of the shingle lengthwise of the projecting portion of the fastener.

3. The combination of a metallic fastener formed with a tongue, a flexible shingle having an opening in its lower end portion through which the tongue passes, and a metallic edging on the lower end of the shingle adjacent the opening.

4. The combination of a metallic fastener having a tongue, a flexible shingle having an opening in its lower end portion through which the tongue passes, a metallic edging on the lower end of the shingle adjacent the opening, and a socket formed in the edging in line with the opening for reception of the projecting end of the tongue.

5. The combination of a metallic fastener having a tongue, and a flexible shingle having an opening in its lower end portion through which the tongue passes, the shingle having its lower end underfolded and being provided with a metallic edging which is wrapped in and around the folded end.

HERBERT ABRAHAM.
